(57) **CLAIM**

The ornamental design for a buckle member for bag, as shown and described.

DESCRIPTION

FIG. 1 is a front, top, and right-side perspective view of a buckle member for bag, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2; and,

FIG. 9 is a cross-sectional view taken along line 9-9 shown in FIG. 2.

The evenly spaced broken lines shown in FIGS. 1-3, 5, and 7-9 depict portions of the buckle member for bag that form no part of the claimed design.

1 Claim, 6 Drawing Sheets
